DEMOUNTABLE SHEAVE

David Lowell Kessler, Denver, Colo., assignor to
 Gates Rubber Company, Denver, Colo., a corporation of Colorado

Application June 19, 1948, Serial No. 34,070

3 Claims. (Cl. 74—230.01)

1

This invention relates to improvements in sheaves, more particularly to sheaves of the multiple groove type employed in connection with multiple V-belt power transmissions, but is not limited to such use.

It is the object of this invention to produce a sheave assembly of a two-part construction, comprising a hub and a rim assembly of such construction that the same rim may be combined with hubs bored for the reception of shafts of different sizes and in which rims of different diameters may be combined with the same hub.

Another object is to produce a sheave of such construction that the hub can be clamped to the shaft by means of the rim so that torque from the shaft can be transmitted through the sheave without the necessity of splines or keys between the shaft and the hub.

Another object is to produce a sheave assembly of such construction that it can be easily and quickly attached to and removed from a shaft.

A further object is to provide a sheave assembly of such construction that the rim portion may be positioned on the hub in two longitudinally different positions.

A still further object is to provide a sheave assembly of such construction that the rim may be removed from the hub while the latter is in position on the shaft so that rims of different sizes may be quickly substituted.

The above and other objects that may appear as the description proceeds are attained by means of a construction and an arrangement of parts that will now be described in detail, and for this purpose reference will be had to the accompanying drawing in which the invention has been illustrated, and in which:

Figure 1 is a diametrical section through a sheave assembly, taken on line 1—1, Figure 2;

Figure 2 is a side elevation of the sheave looking towards the left in Figure 1;

Figure 3 is a section taken on line 3—3, Figure 4;

Figure 4 is a side elevation looking towards the left in Figure 3; and

Figure 5 is a partial section similar to that shown in Figure 1 and shows how a rim like shown in Figure 3 can be employed with the hub to effect additional longitudinal adjustment.

Referring now to the drawing, reference numeral 15 designates the hub which has an axial opening of any desired size and which is provided with an outwardly extending flange 16. Inclined or outwardly tapered surfaces 17 and 17' extend from opposite sides of the flange as shown

2

in Figure 1. The hub and the flange are separated by means of a diametrical saw cut 18 which extends from a point approximately at the inner diameter of flange 16 on one side to the outside and entirely through the flange on the other side in the manner indicated by full and dotted lines in Figure 2. Flange 16 is provided with a plurality of angularly spaced threaded holes 19 for the reception of cap screws 20. The inclined surfaces 17 and 17' are of the same diameter and same inclination. A rim 21 is provided with an inwardly extending web 22 having a tapered opening of somewhat smaller diameter than the normal diameter of inclined surfaces 17 and 17' so that when web 22 is in the position shown in Figure 1 and forced against flange 16 by means of the cap screws 20, the hub will be contracted slightly so as to force the inner surface of the opening therein into frictional engagement with a shaft. Of course it is understood that the opening in the hub must be of such a diameter that the hub can be slid onto the shaft with an easy sliding fit and after it has been properly positioned on the shaft, the hub and rim assembly can then be clamped frictionally to the shaft by tightening the cap screws so as to bring the opposing surfaces of the flange and web into engagement.

Referring now to Figures 1 and 2, it will be observed that flange 16 is nearer one end of the hub than the other. In this specific embodiment, the inclined surface 17 is of the same width as the thickness of web 22 so that when the parts are in assembled and operative position, the end of the hub will be in the same plane as the outer surface of web 22. When the two parts are assembled as shown in Figure 1, the sheave will project a short distance beyond the outer end of the hub. However, if the rim is reversed so as to bring it onto the inclined surface 17', the two parts will still retain substantially the same longitudinal relation as shown in Figure 1. It is to be understood that rim 21 may have either a greater or a lesser number of grooves than those shown and it therefore becomes a great convenience to be able to reverse the parts in the manner made possible due to the double inclined or conical surfaces 17 and 17'.

In Figures 3 and 4 a slightly modified form of construction has been shown. The hub has been designated by reference numeral 15a and is provided with an outwardly extending flange 16a. A frustoconical or inclined surface 17a extends outwardly from the outer surface of flange 16a. Rim 21a has been shown as having five grooves in

stead of four as in Figures 1 and 2 and web 22a is somewhat thicker than web 22 and has the wall of its opening provided with two outwardly flaring tapered surfaces 23. Web 22a is provided with six holes. Those designated by reference numeral 24 are for the reception of cap screws 25. The holes designated by numerals 26 are threaded, but have no corresponding holes in flange 16a. When the sheave assembly shown in Figures 3 and 4 is applied, the rim is positioned either as shown in Figure 3, or it may be reversed; in the latter case it will extend inwardly beyond the inner surface of the hub. Such arrangements are sometimes necessary in connection with certain machinery. After the hub has been positioned on the shaft, screws 25 are tightened, forcing web 22a upwardly along the inclined surface 17a, thereby contracting the hub about the shaft forcing the same into frictional engagement with the shaft. Due to the small taper and to the fact that the cap screws, when properly tightened, will exert a strong force, the hub is contracted above the shaft with sufficient force to form a frictional engagement that will prevent accidental rotation in the absence of keys or splines.

It will be observed that in both forms of the invention shown, flanges 16 and 16a and webs 22 and 22a are positioned to one side of the middle point of each part. This makes it possible to obtain various longitudinal adjustments that are very useful in effecting the proper positioning of the sheaves to bring them into alignment with cooperating sheaves on spaced parallel axes. When the rim is to be removed, for example, if it is to be replaced by one of a greater diameter, the securing bolts are removed and two of them are positioned in the threaded holes 26 and moved inwardly towards the surface of flange 16a, thereby producing a force tending to move the web outwardly and effect a release between the two parts.

It is pointed out that the rim shown in Figures 3 and 5 can be used with the hub illustrated in Figure 1, whereby a variety of adjustments may be effected. In the same manner the rim shown in Figure 1 can be used with the hub shown in Figures 3 and 5. Figure 5 shows how a rim having a flange 22a with oppositely inclined frusto-conical surfaces can be substituted for the one shown in Figure 1 so as to effect additional adjustments in the manner explained in connection with Figures 3 and 4.

With the hub illustrated in Figure 3, two adjustments may be made, one of said adjustments is the one illustrated and the other involves turning the rim in the opposite direction.

With the hub shown in Figure 5 and the rim shown in Figures 3 and 5 for different adjustments may be made, two on each side of the flange.

Having described the invention what is claimed as new is:

1. In a demountable sheave of the power transmission type, comprising a hub having an axial opening for the reception of a shaft, a flange surrounding the hub in a plane perpendicular to its axis, there being an outwardly tapering

frusto-conical surface on each side of the flange, the flange being positioned nearer one end of the hub than the other, the hub and flange having a radial saw kerf, a rim having an inwardly extending flange provided with a central opening, the wall of said opening having two outwardly flaring surfaces of the same taper as the tapers of the frusto-conical surface on the hub, the diameters of the openings in the flange of the rim being slightly smaller than the corresponding outside diameter of the hub, whereby the opening in the hub will be reduced when the rim is in position and forced towards the flange on the hub, the flange being nearer one end of the rim than the other, whereby the hub and flange may be assembled in any one of four different relative longitudinal positions.

2. In a demountable sheave of the power transmission type, comprising a hub having an axial opening for the reception of a shaft, a flange surrounding the hub in a plane perpendicular to the hub axis, the hub having an outwardly tapering frusto-conical surface on one side of the flange, the hub and flange having a radial saw kerf, a rim having an inwardly extending flange provided with a central opening, the opening wall comprising two outwardly flaring frusto-conical surfaces of the same taper as the frusto-conical surfaces on the hub, but of slightly smaller radii, whereby when the rim is positioned on the hub with one of its tapered surfaces in engagement with the outwardly tapered surface of the hub and forced inwardly towards the flange, the opening in the hub will decrease in diameter, the inwardly extending flange on the rim being spaced nearer one end than the other, whereby the hub and rim may be assembled in two different relative longitudinal positions by reversing the rim relative to the hub.

3. In a demountable sheave of the power transmission type, comprising a hub member having an axial opening for the reception of a shaft, a rim having an inwardly extending flange member adapted to axially telescope over the hub member, one of said members having a pair of frusto-conical surfaces extending in opposite directions from a plane therebetween normal to the hub axis, the surfaces intersecting at said plane, at least one frusto-conical surface on the other member engageable with one of said pair of frusto-conical surfaces, a flange surrounding the hub, the last named flange and the hub having a slot therein to permit contraction of the hub on a shaft, and means for drawing said inwardly extending flange member toward the last named flange to secure the rim to the hub and contract the hub on a shaft.
